UNITED STATES PATENT OFFICE.

NORMAN F. NELSON, OF FLUSHING, NEW YORK.

DESIGN FOR A SUIT FOR PLAYING-CARDS.

41,310.

Specification for Design.

Patented Apr. 11, 1911.

Application filed December 27, 1910. Serial No. 599,536. Term of patent 14 years.

To all whom it may concern:

Be it known that I, NORMAN F. NELSON, a citizen of the United States, and residing at Flushing, in the county of Queens, State of New York, have invented a new, original, and ornamental Design for a Suit for Playing-Cards for Card Chess or Check, of which the following is a specification, reference being had to the accompanying drawing, forming part thereof.

The drawing shows the faces of the cards embodying my new design.

I claim:

The ornamental design for a suit for playing cards for card chess or check, as shown.

NORMAN F. NELSON.

Witnesses:

J. W. GREENWOOD,
H. F. DEAN.
